UNITED STATES PATENT OFFICE

135,751

DESIGN FOR AN APPARATUS FOR COLLATING AND POSTING BUSINESS FORMS

Richard C. Browne, Rochester, N. Y., assignor to The Todd Company, Inc., Rochester, N. Y., a corporation of New York

Application March 8, 1943, Serial No. 109,696

Term of patent 14 years

To all whom it may concern:

Be it known that I, Richard C. Browne, a citizen of the United States and a resident of Rochester, in the county of Monroe and State of New York, have invented a new, original, and ornamental Design for an Apparatus for Collating and Posting Business Forms, of which the following is a specification, reference being had to the accompanying drawings, forming a part thereof.

Fig. 1 is a perspective view of an apparatus for collating and posting business forms embodying my design, looking at it obliquely from one side.

Fig. 2 is a plan view thereof.

Fig. 3 is a side elevational view thereof.

I claim:

The ornamental design for an apparatus for collating and posting business forms, substantially as shown.

RICHARD C. BROWNE.
